PUMPING SYSTEM

Milford W. Hartmann, Hutchinson, Kans.

Application April 3, 1939, Serial No. 265,679

3 Claims. (Cl. 103—5)

This invention relates to pumps, and in particular to a pumping system including a centrifugal pump in which great flexibility of pumping characteristics is attained.

An object of my invention is to provide a water supply pressure system including a centrifugal pump and an hydraulic jet in which higher pressures may be attained than are ordinarily developed with a centrifugal pump. Another object is to provide a water pressure system including a centrifugal pump and an hydraulic jet in which large volumes of water at relatively low pressures may be pumped and in which smaller amounts of water at higher pressures than may be obtained ordinarily from a centrifugal pump may also be pumped. Another object is to provide an ejector device which in a pumping system including a centrifugal pump permits a range of delivery characteristics from high volume of liquid at low pressure and low volume at high pressure. Still another object is to provide an ejector with a check-valved by-pass. Another object is to provide a check valve of improved structure.

These and other objects are attained by my invention, which will be best understood by reference to the accompanying drawing in which:

Fig. 1 is a vertical section of my ejector device;

Fig. 2 is a view in elevation of my pump and water pressure system;

Fig. 3 is an enlarged view of my improved check valve;

Fig. 4 is a cross-sectional view taken on the line 4—4 of Fig. 3;

Fig. 5 is another cross-sectional view as in Fig. 4 with the annular valve ring removed;

Fig. 6 is an enlarged vertical section of the foot valve of my system.

Referring to the drawing, the centrifugal type pump 11 operatively connected to a motor 12, 40 draws water through suction pipe 13 from a well 14, and through discharge pipe 15 delivers water to a pressure storage tank 16. A pressure actuated electrical switch is indicated at 17, connected to the discharge pipe 15 by pipe 18 and 45 electrically to the motor 12 by conduit encased wires 19, this device functioning to automatically stop the motor 12 when the pressure in the tank 16 has reached a predetermined maximum, and to start the motor again when the pressure 50 15 is also the delivery pipe from the tank, a water outlet pipe 49 with valve 50 delivering the water where required.

The ejector device 21 is attached in the well to 55

the suction pipe 13, and below the ejector device 21, the foot valve 22 is connected by the pipe 51. The ejector device 21 is also connected to the pressure or discharge pipe 15 from the pump, by the recirculating pipe 23, having a control valve 24. Within the ejector device 21 an upwardly pointed nozzle 25 is supported within the nozzle housing 26 by the side-entering tube 27 which connects with the recirculating pipe 23. Above the nozzle 25 is an eductor tube 28 supported within the eductor housing 36 by the hub or partition 29 having ports 30 for the passage of liquid through the partition. The partition 29 is held by the collar 35 at the threaded connection between the nozzle housing 26 and the eductor housing 36. The ports 30 are controlled by the annular valve body 31, which when the valve is closed, rests on inner conical seat 32 and outer inverted conical seat 33. The annular valve body or ring 31 is free to move in the space between the seats 32 and 33 and the stops 34, which are attached to the eductor tube 28 at a point sufficiently above the valve seats so that the valve ring 31 when lifted by the flow of water will give an unobstructed passage through the ports 30.

The eductor tube 28 is preferably a cone-shaped tube having a short cylindrical portion 37 at the small end adjacent the nozzle 25. The length of this cylindrical portion is about six times its inside diameter. The conical portion tapers down to the cylindrical portion 37 so that the angle of the cone is about eleven degrees. The diameter of the eductor housing 36 is large enough so that the upper end of the conical portion of the eductor tube does not restrict the flow of water, the effective cross-section for liquid outside the tube being at least as great as that of the pipe 13.

The footvalve or check valve 22 in the well is similar in construction to the ring valve in the ejector device, the stops 34a being attached to a threaded stud 39 in the hub or partition 29, which is threaded into the footvalve casing 40, which in turn has a threaded upper end for attachment to a pipe, for example, the pipe 51 in Fig. 2. The annular valve body or ring 31 is preferably made of molded rubber or rubber-like composition, hard enough to maintain its shape, but soft enough to form a tight seal on the valve seats 32 and 33. The valve seating surfaces are conical, the outer one 33 being an inverted cone, and their surfaces are steep to eliminate the possibility of lodgement of sand or sediment on the seats which would prevent sealing of the

valve. The valve ring 31 floats in the liquid moving upwardly and there is no opportunity for the accidental binding of the ring, and no wearing part to shorten the life of the valve.

The action of my valved ejector device will be best understood by reference to the centrifugal pump pressure water system shown in Fig. 2, together with the details shown in Figs. 1, 3, 4, 5 and 6. In using such a system for household service, it is desirable to have a water supply available at all times at pressures of 35 to 70 pounds per square inch, the amount of water to be delivered at these household pressures in a given time being relatively small. Such pressures are not practicable when using a centrifugal pump without the aid of an ejector. For other purposes, such as irrigation of gardens and lawns, a large volume of water at low pressure may be desired from the same system. When, however, an ejector of the usual type, (without my valving arrangement) is placed on the suction side of the pump, the volume capacity is thereby greatly reduced, because the water must all go through the jet and eductor tube, which are necessarily constricted.

While another suction pipe line, with hand operated valves might be used to by-pass the ejector, and permit the centrifugal pump to deliver a large volume of water at low pressure, this arrangement is impractical, and its obvious drawbacks are avoided by the use of my valved ejector device.

When the pump is operating against a pressure such as that of the closed system represented in Fig. 2, the ejector action of the recirculated water through the tube 23 and the open valve 24, through nozzle 25 and the eductor tube 28, is to put into the tank 16 a relatively small volume of water at a high pressure, a part of the water of course being recirculated. While so operating against pressure, there is a higher pressure in the water above the ring valve than in the water from the well immediately surrounding the nozzle 25, and consequently the ring valve 31 remains tightly closed on the seats 32 and 33, and no water passes through the valved ports 30.

If, now, the valve 50 be opened and water flows from the system, the pressure immediately drops, and if the rate of discharge of water from the system is rapid, there is no opportunity to build up pressure in the tank again. The delivery pressure is low, and the eductor exerts little effect on the pressure in the system. The pump, delivering a higher volume of water at the lower delivery pressure, reduces the pressure above the ring valve, which then sucks open, and permits the pump to function substantially as if there were no ejector in the suction line. If the valve 24 is closed so that no water recirculates through the ejector, the action is the same as when no ejector is present, the pump 11 simply sucking the water from the well through the footvalve 22, the pipe 51, the ports 30 and around the eductor tube 28 through the housings 36 and 37.

Under the conditions of building up pressure in the system, the action would be as follows: the valve 24 being opened and the valve 50 closed with the system at low pressure, the pump 11 would draw water through the ports 30 and also through the eductor tube 28, and a small amount of water would recirculate through the pipe 23 and the nozzle 25. The pressure would be built up to the maximum available for the centrifugal pump alone (without an ejector). The water recirculated through the nozzle would attain a

higher and higher velocity as the pressure built up in the system and in line 23, and would become an added factor in increasing the water pressure until it counteracts the suction in the housing 36 above the ring valve 31, and this valve closes automatically, so that all of the water passes through the eductor tube, the pressure continuing to build up as the proportion of recirculated water through the nozzle 25 becomes greater and greater. When the pressure in the system has built up to the desired maximum, the automatic pressure controlled switch 17 stops the motor.

In place of the hand operated valve 24 shown in the recirculating pipe line 23, I may use an automatic pressure actuated valve which will fully open when the water in the discharge line of the pump reaches the pressure at which the efficiency of the centrifugal pump is becoming seriously decreased. The opening of this valve automatically will start the action of the ejector device and increase the pressure as above described.

While I have described a preferred form of my invention, I do not wish to be limited thereby, but restrict my invention only insofar as required by the prior art and the spirit of the appended claims.

I claim:

- 30 1. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in the one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, check-valved ports through said partition, connecting means in said housing above the eductor tube for said suction pipe communicating with the suction side of the pump, and connecting means in said housing below said nozzle for said suction pipe leading down to said foot-valve beneath the liquid in a reservoir.
- 35 2. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, ports in said partition arranged in a circle around said eductor tube, a ring-shaped valve seat on the upper side of said partition communicating with said ports, a rubber-like ring adapted to coact with said seat to serve as a valve, connecting means in said housing above the eductor tube for said suction pipe communicating with the suction side of the pump, and connecting means in said housing below said nozzle for
- 40 3. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for
- 45 4. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for
- 50 5. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for
- 55 6. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for
- 60 7. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for
- 65 8. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for
- 70 9. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for
- 75 10. In a pumping system, a centrifugal pump, a suction pipe connected to said pump, a foot-valve at the lower end of said suction pipe, and an ejector device in said suction pipe intermediate the pump and the foot-valve, said ejector device comprising a housing having a recirculation pipe from the discharge of said pump connected in one side thereof, an upwardly directed nozzle attached within the housing to said recirculation pipe, a partition wall in said housing above said nozzle, an eductor tube having a short cylindrical section and a longer conical section in which the projected wall angle is about eleven degrees, the end of the cylindrical section extending through and supported by said partition, connecting means in said housing above the eductor tube for said suction pipe communicating with the suction side of the pump, and connecting means in said housing below said nozzle for

said suction pipe leading down to said foot-valve beneath the liquid in a reservoir.

3. In a pumping system, a centrifugal pump, a suction pipe connected to said pump, a foot-valve at the lower end of said suction pipe, and an ejector device in said suction pipe intermediate the pump and the foot-valve, said ejector comprising a nozzle housing having a side entering tube, a recirculation pipe connected to the discharge of said pump, said side-entering tube on the inside being turned upwardly and adapted to engage a nozzle, a nozzle attached to said tube, connecting means in said housing below said side tube for said suction pipe leading down to the foot-valve in a well, a partition wall disposed above said nozzle, a tubular opening through said partition wall centered with said nozzle and provided with a wide-angled conical

port directly above said nozzle, an eductor tube attached in said opening concentrically with said conical port and said nozzle, an eductor housing attached above said partition to said nozzle housing and having connecting means to said suction pipe above the larger end of said eductor tube leading to the suction side of the pump, said eductor tube having a short cylindrical portion immediately above said nozzle and a long conical portion of about eleven degrees cone angle, said partition also being provided with through ports arranged in a circle around said eductor tube, a ring-shaped valve seat on the upper side of said partition at the ends of said ports, a rubber-like ring adapted to coact with said seat at times to close said ports, and stop means to limit the upward movement of said ring.

MILFORD W. HARTMANN.
